(57) **CLAIM**

The ornamental design for a milk bottle, as shown and described.

DESCRIPTION

FIG. 1 is a front view of a first embodiment of the present design;

FIG. 2 is a rear side view thereof;

FIG. 3 is a left side view thereof;

FIG. 4 is a right side view thereof;

FIG. 5 is a top view thereof;

FIG. 6 is a bottom view thereof;

FIG. 7 is a front view a second embodiment of the present design;

FIG. 8 is a rear side view thereof;

FIG. 9 is a left side view thereof;

FIG. 10 is a right side view thereof;

FIG. 11 is a top view thereof; and,

FIG. 12 is a bottom view thereof.

The solid black shading, which appears in the second embodiment, is used to show contrast in appearance. The broken lines show portions of the milk bottle that form no part of the claimed design.

1 Claim, 6 Drawing Sheets
